(57) **CLAIM**

The ornamental design for a towel warmer bucket, as shown and described.

DESCRIPTION

FIG. 1 is a front, right and top perspective view of a towel warmer bucket, showing our new design;

FIG. 2 is a rear, left and bottom perspective view thereof;

FIG. 3 is a perspective view of the towel warmer bucket in an opening state;

FIG. 4 is a perspective view of the towel warmer bucket in a folding state;

FIG. 5 is a front view thereof;

FIG. 6 is a rear view thereof;

FIG. 7 is a left side view thereof;

FIG. 8 is a right side view thereof;

FIG. 9 is a top plan view thereof;

FIG. 10 is a bottom plan view thereof; and,

FIG. 11 is a top plan view of FIG. 3.

The broken lines shown in the drawings illustrate portions of the towel warmer bucket that form no part of the claimed design.
